CALENDAR

Filed Sept. 28, 1926

Inventor

HUGH E. SHEDD,

Hugh E. Shedd

Attorney

UNITED STATES PATENT OFFICE.

HUGH E. SHEDD, OF MINNEAPOLIS, MINNESOTA.

CALENDAR.

Application filed September 28, 1926. Serial No. 138,289.

This invention relates to improvements in calendars of the type embodying a plurality of leaves, each of which has printed thereon data to indicate the month, date, and day, and spaces for making memoranda.

In calendars of this general type, considerable difficulty is experienced in retaining the base flat when sheets with memoranda thereon have been folded back to preserve the sheets for a permanent record.

According to my invention, I provide a calendar with a rigid base to which the series of leaves is fastened, and in the base above the leaves an opening is formed, so that when the leaves are used, they may be folded back through the opening and against the rear surface of the base and by suitable means the used leaves may be retained flat against the base.

One of the principal objects of the invention is to provide a simple and inexpensive means for retaining the used leaves flat against the rear surface of the base of the calendar to prevent the leaves spreading and becoming abused.

A further object of the invention is to provide certain specific data in the spaces provided for the days and dates of the week, to improve the usefulness of the calendar.

In the drawings,

Fig. 1 is a perspective view of my improved calendar.

Fig. 2 is a section of the same.

Fig. 3 is a detailed rear view.

Figs. 4 and 5 are detail sections.

Fig. 1 indicates a base formed near its upper end with a slot 2, and on the front side of the base below the slot is fastened a series of sheets or leaves to form a calendar.

Each leaf, as shown, is divided into seven spaces corresponding to the number of days in a week, and these spaces are sub-divided, as shown at 3, and in each sub-divided space is printed in bold type the day of the week

and the date. In each sub-divided space, adjacent the date, is printed in small type, as shown at 4, the dates of the corresponding days throughout the particular month, and also in the sub-divided spaces appear consecutive numerals to indicate the number of days in a particular year.

Near the top of the base above the opening 2, is an eye 5 by means of which the calendar may be supported on a hook or the like. In addition to this function, the

eye affords a means for securing the end 6 of a leaf retainer 7. As shown, the retainer consists of a thin flat resilient strip of metal 8, its upper end being bent to pass through the opening which receives the eyelet. The retainer extends downwardly on the rear of the base and its lower end is turned upwardly to form a hook 9 which is passed through a small opening 10, in the base to provide means for holding the lower end of the retainer in position. The opening 10 through which the lower end of the retainer passes is somewhat larger than the thickness of the metal strip, so as to permit of a slight play to readily permit the strip to yield or bulge when the used calendar sheets are folded back as will be later described.

When a resilient metal strip is used as a retainer, it is tensioned to form a slight bulge as shown at 12, to assist in clamping the sheets tight against the base. The retainer may be in the form of a strip of strong paper or cloth, or a cord or resilient band, but metal being the more durable, serves the purpose more efficiently.

When the week represented by a leaf on the front of the base has passed, the lower end is turned and passed through the opening 2, and is then pulled down on the reverse side of the base between the latter and the resilient metal strip, so that the used leaves are preserved flat as a permanent record. As the number of used leaves increase, the resilient strip will readily yield to accommodate the increase bulk, due to the tension of the metal and the play of the bent end of the strip in opening 10, thus holding the leaves snugly up against the base. This in effect affords a more or less increased thickness of the base, so that at all times a substantially flat surface is maintained to afford convenience in writing on the leaves on the front of the base.

The arrangement of numerals in the sub-divided spaces affords a convenient means of determining at a glance the dates of a corresponding day throughout the month. For instance the third day of January, 1927, comes on Monday. In the sub-divided space with the numeral 3 in bold type appear the smaller numerals 10—17—24—31, which indicate that these dates will be Mondays throughout the month. Thus, at a glance, one can readily and conveniently make an

engagement for a certain day and date in the month, which is a time saver to the busy man.

The arrows shown at 15 merely indicate that the smaller numerals in the sub-divided spaces are related to the more prominent numeral indicating the date of the month, and the fact that the more prominent numeral should be read as a part of the group of 10 smaller numerals. That is to say, all the Mondays for the entire month include both the prominent and smaller numerals, but the prominent numeral indicates the current Monday. Thus, considering Monday, January 3, 1927, the arrow 15 points to the prominent numeral 3, indicating that all the Mondays in the month will be dated as follows—3—10—17—24—31. If the current date, or prominent numeral comes after 20 the first smaller numeral, as for instance Saturday, January 8, 1927, the smaller numerals will be read first, then the arrow indicating the current date in the group will point to the prominent numeral, and 25 the combined figures will then read 1—8—15—22—29.

It is of course to be understood that the invention is in no way limited to a calendar employing leaves to indicate the days and 30 dates for a full week. The invention is just as effective when used with calendars using leaves showing a single date, or it may be used in connection with memorandum pads where it is desired to preserve the 35 leaves for a permanent record.

I am aware it is not new in the art to provide means for holding the leaves on the reverse side of the base of a calendar of this type, as for instance in the patent to 40 Chrysander, No. 1,375,567. However, I am not aware of a construction being old where the front of the base is preserved flat so

as to form a substantial surface for writing on the "live sheets" with means on the reverse of the base to preserve the used leaves. 45

What I claim is:

1. A device of the character described, comprising a base, and a leaf retainer on the rear of the base adapted to retain and preserve used sheets, said retainer being 50 secured to the base and being of greater length than the length of the sheets when folded on the rear of the base.

2. A device of the character described comprising a base having an opening formed 55 therein, and a leaf retainer secured to the rear of the base and extending over the opening and being of greater length than the length of leaves when extended through the opening and folded against the rear of 60 the base.

3. A device of the character described comprising a base having an opening formed therein, and a leaf retainer having its upper 65 end fastened to the base above the opening and its lower end anchored to the base, said retainer being of a length as to engage leaves and hold same against the rear of the base when passed through the opening.

4. A device of the class described comprising a base having an opening formed 70 therein, a yielding leaf retainer secured to the rear of the base and extending across the opening.

5. A device of the class described comprising a base having an opening formed 75 therein, a yielding leaf retainer secured to the rear of the base and extending across the opening, means for permanently fastening the upper end of the yielding retainer 80 to the base, and means for loosely anchoring the lower end of the retainer to the base.

In testimony whereof I affix my signature.
HUGH E. SHEDD.
